BUST-SUPPORTING GARMENT

Marguerite Renée Williams, New York, N. Y., assignor to La Trique Brassieres, New York, N. Y., a partnership

Application October 26, 1950, Serial No. 192,176

4 Claims. (Cl. 2—42)

1

My invention relates to improvements in bust-supporting garments and has particular reference to an improved brassière of the type having reinforcing inserts.

Brassières of the aforementioned type are generally strapless and are provided with flexible and springy wire inserts which by spring tension clamp the garment tightly to the bust. Such types of brassières are often uncomfortable in wearing and do not supply adequate bust-confining properties during movement of the body.

I provide a bust-supporting garment which has breast-supporting and separating pockets or cups supported by shoulder straps, the pockets being interconnected only by overlapping rigid members each of which extends around a peripheral portion of both pockets.

It is the principal object of my invention to provide a bust-supporting garment in which the breast-retaining pockets or cups are pivotally attached to each other in such a manner as to allow full freedom of movement of one pocket while leaving the other unaffected, as when the wearer raises one shoulder.

Another object of the invention is the provision of a bust-supporting garment which conforms to the configuration of the body and adapts itself to bodily movement, the garment being held in position without excess tension of the supporting straps and providing excellent bust supporting, confining and separating characteristics without sacrificing comfort.

Still another object of the invention is the provision of a bust-supporting garment containing rigid inserts, so arranged as to eliminate pressure under the breasts, while at the same time eliminating gapping at the top and bottom of the garment and bulging at the center thereof.

Other objects and advantages of the invention will be readily apparent in the course of the following specification when taken in connection with the accompanying drawings, in which:

Fig. 1 is a front elevation of a brassière made according to my invention;

Fig. 2 is a rear elevation of the central portion of the brassière;

Fig. 3 is an elevational view of the rigid elements of the brassière partially enclosed in their tubular casings which are broken away for convenience of illustration. In this view the rigid elements are shown in a position identical to that of Fig. 2; and

Fig. 4 is a section taken along line 4—4 of Fig. 2.

2

The drawings show my invention as applied to a brassière, although it is to be understood that the invention may be as readily applied to any other type of bust-supporting garment such as a foundation garment having a brassière portion, a bathing suit, etc.

The brassière has the usual pair of breast-receiving pockets or cups 10 and 11 which are made of a suitable fabric and may have any type of conventional design. The pockets 10 and 11 may be optionally provided with the usual fabric reinforcing strips 12. The outer edge of each pocket 10 and 11 is secured to the edge of respective back straps 13 and 14. Said back straps 13 and 14 extend around the sides and back of the wearer and terminate in attached elastic strips 15 and 16 which may be connected by a clasp 17 or similar means of attachment. A shoulder strap 18 connects the top edge of pocket 10 with the top edge of the back strap 13, while a similar shoulder strap 19 connects the pocket 11 with the back strap 14.

The pockets 10 and 11 have respective bottom edges 10a and 11a, and top edges 10b and 11b. The pockets 10 and 11 also have respective arcuate inner side edges 10c and 11c which are outwardly inclined from the respective bottom edges 10a and 11a to the top edges 10b and 11b, so that they join the top edges 10b and 11b approximately above center of the bottom edges 10a and 11a.

The pockets 10 and 11 are joined by a pair of rigid insert members 20 and 21 which may be made in the shape of rigid cylindrical rods as shown in Fig. 3, or may be made in flat strip form. The insert members 20 and 21 may be formed of rigid metal or plastic, and each is pre-shaped to conform to the shape of the pockets 10 and 11. The insert members 20 and 21 are preferably flattened or rounded at their ends, as indicated at 22, to prevent discomfort or injury to the wearer. In the drawings, the insert members 20 and 21 are shown as having an elongated or flattened S-shape, which shape may of course be varied depending upon the size and shape of the pockets 10 and 11.

The insert members 20 and 21 are respectively encased in tubular fabric coverings 23 and 24, which are appreciably longer than said insert members 20 and 21. The coverings 23 and 24 may be conveniently made of two elongated strips of fabric material connected along their longitudinal edges by rows of stitching 25, as shown in Fig. 4.

One end of the covering 23 is secured to the

pocket 11 at the juncture of the top edge 11b with the side edge 11c, by stitching 23, which stitching may also serve to close the end of said covering 23 as well as to secure the shoulder strap 19 to the pocket 11. In an identical manner one end of the covering 24 is secured to pocket 10 by stitching 27.

The other end of the coverings 23 and 24 may be secured to the respective bottom edges 10a and 11a of the pockets 10 and 11 by stitching 28 and 29, or they may be secured to the lower edges of the side and back portions 14 and 13, as shown in Fig. 2.

As indicated in broken line in Fig. 2, the top end of the insert member 20 is located adjacent the stitching 26 of pocket 11 and the bottom end of the insert member 21 is well spaced from the stitching 28 of pocket 10, thereby providing a free and unfilled space 23a at the lower end of covering 23. Similarly, a free and unfilled space 24a is provided at the lower end of covering 24.

Fig. 2 shows two alternate means for holding the coverings 23 and 24 in flush alignment with peripheral edge portions of the pockets 10 and 11. One or more loops 30 are sewn along the respective bottom edges 10a and 11a of pockets 10 and 11. Similar loops 31 may be sewn at suitable spaced intervals along the inner side edges of the pockets, as shown attached to the inner side edge 11c of pocket 11 in Fig. 2. The coverings 23 and 24 and their enclosed rigid insert members 20 and 21 fit loosely through these loops 30 and 31 so that they may move slidably in a longitudinal direction therethrough relative to the pockets 10 and 11. Alternatively the inner side edges of the pockets 10 and 11 may be lined with continuous fabric casings 31a (as shown attached to the inner side edge 10c of pocket 10 in Fig. 2), in which the coverings and insert members may be slidably held.

The container 23 therefore extends along the inner side edge 11c of pocket 11 and then crosses over to the bottom edge 10a of pocket 10, being held in place in alignment with these edges by the loops 30 and 31 or the casings 31a. Similarly, the container 24 is held in place along the inner side edge 10c of pocket 10 and the bottom edge 11a of pocket 11, the said container 24 crossing and overlapping the container 23 at a point of intersection 32 located between the pockets adjacent the bottom edges 10a and 11a of said pockets 10 and 11. The rigid insert members 20 and 21 extend along the respective inner side edges 11c and 10c of pockets 11 and 10 and then cross to the bottom edges 10a and 11a of the opposite pockets, extending approximately half-way across these bottom edges.

The pockets 10 and 11 are thus held spaced from each other, and have a flexible connection at their lower ends provided by the loosely-mounted flexible strips 28 and 29 which form a part of each pocket.

Excess movement of the pockets 10 and 11 relative to one another may be prevented by the provision of a flexible fabric cross-band 33 which connects the lower inner ends of pockets 10 and 11. The ends of this cross-band 33 may be stitched at the point of intersection of the inner side edges 10c and 11c of pockets 10 and 11 with the bottom edges 10a and 11a. The ends of the cross-band 33 may also slidably house the coverings 23 and 24 adjacent their point of intersection 32, as shown in Fig. 2. Alternatively, the same result may be achieved by loosely tying together the coverings 23 and 24 at their point

of intersection 32, as by a fabric loop or band 34 (shown in Fig. 3).

When the garment is worn on the body, the flexible connection between the pockets 10 and 11, afforded by the insert members 20 and 21, enables one of the pockets to be moved independently of the other and without distorting the other. The wearer is thus afforded a wide freedom of bodily movement. At the same time, the breast confining and separating functions of the garment are not sacrificed. When the wearer, for example, lifts one shoulder, the corresponding pocket will be raised, but due to the sliding movement of the insert members and their coverings through the loops or casings attached to the edge of the pockets, the other pocket will remain unaffected in its normal position.

It should also be noted that the arcuate divergent shapes of the inner side edges 10c and 11c of the pockets 10 and 11 afford a wide V-shaped space between the pockets so that the garment may be worn with dresses having a plunging neck-line. This divergent shape of the inner side edges 10c and 11c is made possible by the use of the preshaped rigidly insert members 20 and 21 which efficiently maintain the shape of the pockets along these inner side edges.

While the brassière is primarily held on the body by the shoulder straps 13 and 14 and the back straps 13 and 14, the rigid insert members 20 and 21 maintain the pockets 10 and 11 held firmly to the bust, so that great tension on the shoulder and back straps is not required. The brassière is thus adapted to provide more comfort to the wearer than the usual garment of this type. It should also be noted that the rigid insert members 20 and 21 press against the breasts only along the inner side edges of the pockets and not at the bottom edges, so that there is no appreciable pressure under the breasts.

The provision of the free and unfilled portions 23a and 24a of the coverings 23 and 24 afford a latitude of movement of the lower portion of each pocket 10 and 11 without affecting the corresponding insert members 20 and 21. Thus, during movement of the body, the contraction of the lower portion of either pocket will not cause the bunching or outward bowing of the central portion of the garment corresponding to the point 32, but this central point will always remain pressed against the breastbone of the body, so that the breasts will remain well separated.

While preferred embodiments of the invention have been shown and described herein, it is obvious that numerous omissions, changes, and additions may be made in the invention without departing from the spirit and scope thereof.

I claim:

1. A bust-supporting garment comprising a pair of spaced breast receiving pockets, a shoulder strap supporting each pocket, a pair of back straps respectively secured to the outer edge of said pockets and adapted to be interconnected at the back of the wearer, a pair of identical, substantially S-shaped, rigid and inflexible insert members, and a flexible tubular casing housing each of said insert members, said casing being secured at one end to the top of one pocket and at the other end to the bottom of the other pocket, said pockets having flexible fabric retaining members secured along the inner side edges and bottom edges thereof, said casings extending slidably through said retaining members, each of said contained insert members extend-

ing along the inner side edge of one pocket and along at least part of the bottom edge of the other pocket, said insert members and said casings overlapping in the space between said pockets at a point adjacent the bottom edges of said pockets.

2. A bust supporting garment according to claim 1 in which the casings are appreciably longer than the contained insert members, said casings being connected at their ends to the bottom edge of said pockets adjacent the outer side thereof, said casings having free and unfilled spaces adjacent said ends.

3. A bust supporting garment according to claim 1 in which the inner side edges of said pockets are upwardly divergent to provide a wide V-shaped space between said pockets, said space being bordered by said rigid insert members.

4. A bust-supporting garment comprising a pair of laterally spaced breast-receiving pockets having respective bottom edges and having respective inner side edges which extend upwardly from the proximate ends of said bottom edges and which diverge outwardly, a pair of rigid S-shaped insert elements each shaped to conform to the bottom edge of one pocket and the inner side edge of the other pocket, each of said insert elements being contained in a resilient casing which is longer than its respective insert element, each of said casings being secured at one end

to the top edge of one pocket and at the other end to the bottom edge of the other pocket, each of said insert elements extending from the top edge of one pocket along the inner side edge of said pocket, and then crossing over to the other pocket and extending at least partially along the bottom edge thereof, said pockets having tubular retaining means at the inner side and bottom edges thereof to hold said insert elements and casings in alinement with said edges, said casings being slideable within said retaining means, said casings and contained insert elements overlapping each other between said pockets at a point adjacent the bottom edges of said pockets.

MARGUERITE RENÉE WILLIAMS.
